Primary Examiner — Mitchell I. Siegel(74) *Attorney, Agent, or Firm* — Mark Malek; Widerman Malek, PL(57) **CLAIM**

The ornamental design for a swing cover, as shown and described.

DESCRIPTION

FIG. 1 is a bottom perspective view of a swing seat cover according to the present invention;

FIG. 2 is a bottom plan view of the swing cover illustrated in FIG. 1.

FIG. 3 is a top plan view of the swing cover illustrated in FIG. 1.

FIG. 4 is a side elevation view of the swing cover illustrated in FIG. 1.

FIG. 5 is a front elevation view of the swing cover illustrated in FIG. 1; and,

FIG. 6 is a bottom perspective view of the swing seat cover illustrated in FIG. 1 being shown with unclaimed elements. The broken lines shown in FIGS. 1-6 are included for the purpose of illustrating unclaimed subject matter and forms no part of the claimed design.

1 Claim, 4 Drawing Sheets(56)
